(57) **CLAIM**

The ornamental design for a front grille guard for trucks, as shown and described.

DESCRIPTION

FIG. 1 is a front perspective view of a front grille guard for trucks showing my new design;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines represent portions of the structure that form no part of the claim. The dot-dashed lines represent boundary lines that form no part of the claim.
